BOTTLE DISPLAY RACK

Filed April 11, 1932

Fig. 3.

UNITED STATES PATENT OFFICE

HALLET E. KWAPIL, OF RACINE, WISCONSIN

BOTTLE DISPLAY RACK

Application filed April 11, 1932. Serial No. 604,517.

My invention refers to bottle display racks, and it has for its object to provide a simple, economical and durable display rack embodying a plurality of disc sections having notches adapted to receive the necks of bottles, whereby they are suspended for display purposes.

With the above and other objects in view, the invention consists in certain peculiarities of construction and combination of parts, as will be hereinafter fully set forth with reference to the accompanying drawing and subsequently claimed.

In the drawing:

15 Figure 1 represents a sectional elevation of a display rack embodying the features of my invention, the section being indicated by line 1-1 of Figure 2.

20 Figure 2 is a sectional plan view of the same, the section being indicated by line 2-2 of Figure 1, and

Figure 3 is a sectional plan view, as indicated by the line 3-3 of Figure 1.

Referring by characters to the drawing, 25 the numerals 1 and 2 represent rings having radial notches 3-3' therein for the reception of necks of standard bottles, which may be adjusted within the slots and suspended, bottles being indicated in their suspended 30 position at A and B. A third solid disc 4 may be provided, which is arranged intermediate of the rings 1 and 2, and the rings, as shown, together with the disc, are connected by tubular legs 5, which are spread 35 or inclined from top to bottom, as shown.

The upper ends of the legs, as indicated in Figure 1, are soldered, or otherwise connected, to the ring 1, and also similarly connected to the disc 4-4, the said legs being 40 passed through apertures in the lower ring 2 with a solder connection.

It will be noted, however, that while I have shown legs in tubular form, they may be solid, and furthermore they may be secured in any desired manner. As for example, stove bolts may be employed to secure the various ring elements and discs together in connection with the legs, and the legs, when thus secured, form a rigid 45 basis for the structure which is of skeleton

form and which will present a pleasing appearance to the eye. It will also be observed that while I have shown a display rack in three tiers, it is obvious that I may multiply the tiers indefinitely in order to 55 display a greater volume of bottles.

It is also understood that while I have shown the racks adapted to rest upon the supporting legs 4, I may, without departing from the spirit of my invention, in some 60 cases suspend the rack upon a wall with suitable brace legs or ties, and I may also vary the construction by forming the rack with semi-rings, or in other words by splitting the rings in halves. The back of the 65 rack would then rest flush against the wall and the halves would provide a double series of bottle racks. Thus economy in material would be effected.

It is also understood that while I have 70 shown the metal rings and discs stamped out with sharp inner and outer edges, I may in some cases fold over the inner edges to form beads or flanges for strengthening purposes.

Great economy is effected in the construction of this rack, due to the fact that a circular solid blank is first formed, the outer edges of which would be stamped with the radial notches shown in Figure 1. The next 80 progressive ring would be stamped from the inner edge of this ring, as shown in Figure 1, followed by a third stamped ring, if desired, with notches in its periphery, but in this exemplification of my invention the 85 solid metal stamped from the second ring, which would be the stock removed from ring 1, would be left in its solid state, as a disc, the same being indicated by the numeral 4 90 and shown in Figures 1 and 3 of the drawing. This solid disc is utilized as a shelf adjacent to the upper ring 1, whereby a plurality of bottles may be supported thereon, as indicated in dotted lines. Thus, the series 95 of rows of bottles in display would be suspended around the various notched rings, and a second series could be displayed by arranging them upon the solid disc, in such manner that the upper portion of the bottles would be projected above the ring 1 to 100

present a uniform and pleasing appearance or finish for the suspended display.

Thus, the method of manufacture just mentioned is an important feature of my invention, due to utilization of all waste and economy in structure.

While I have shown the rack as provided with two rings, it is obvious that others may be added, and also supplemental leg sections may be added to extend the parts, these sections being connected by threaded couplings.

It is also within the province of my invention to vary the shape of the radially notched discs; that is, the same may be rectangular or polygonal in shape and it is possible to arrange the racks with the notches so that it could suspend the bottles from their racks irrespective of sizes.

20 I claim:—

A display rack for bottles comprising upper and lower flat rings, said upper ring being of less diameter than the lower ring, a supporting plate of disc shape disposed between the rings and of less diameter than the upper ring, and supporting standards diverging toward their lower ends and extending through the lower ring and connected to the periphery of the plate and to the lower face of the upper ring, said rings being provided with peripheral notches adapted to receive the necks of bottles.

In testimony that I claim the foregoing I have hereunto set my hand at Milwaukee, in the county of Milwaukee and State of Wisconsin.

HALLET E. KWAPIL.
